To all whom it may concern:

Be it known that I, Julia Vallee, a citizen of the United States of America, residing in New York city, in the Borough of Manhattan, county and State of New York, have invented a new, original, and ornamental Design for a Dress, of which the following is a specification, reference being had to the accompanying drawing, forming part thereof, wherein,

Figure 1 is a front view of a dress showing my new design.

The characteristic feature of my design resides in the combination on the dress as shown, of the button trim on the front waist section, alternated with stitching on the yoke, as shown.

I claim:

The ornamental design for a dress, substantially as shown and described.

JULIA VALLEE.
